COMBINED BEVERAGE CAN HOLDER AND LID

John J. Doolittle, 411 59th Ave Terrace W.,
Bradenton, Fla. 33507

Filed Oct. 16, 1972, Ser. No. 297,815

Term of patent 14 years

Int. Cl. D7—06

U.S. Cl. D7—70

FIG. 1

FIG. 5

FIG. 2

FIG. 3

FIG. 6

FIG. 1 is a top plan view of a combined beverage can holder and lid showing my new design;

FIG. 2 is a side elevational view thereof;

FIG. 3 is a right side view thereof;

FIG. 4 is a bottom plan view thereof;

FIG. 5 is a top plan view thereof, the lid in open position;

FIG. 6 is a fragmentary side view similar to FIG. 2, but with the lid in an open position; and

FIG. 7 is a fragmentary elevational view similar to FIG. 2 showing a modification of the hinge connection portion thereof.

I claim:

The ornamental design for a combined beverage can holder and lid, as shown and described.
